E. H. BASTABLE.

MACHINE FOR OPERATING UPON SHOES.

APPLICATION FILED MAR. 13, 1916.

1,248,791.

Patented Dec. 4, 1917.

Inventor:

Edward H. Bastable

By his attorney

Phillips, Bastable & Fitch

UNITED STATES PATENT OFFICE.

EDWARD H. BASTABLE, OF SOUTH BRAINTREE, MASSACHUSETTS, ASSIGNOR TO UNITED SHOE MACHINERY COMPANY, OF PATERSON, NEW JERSEY, A CORPORATION OF NEW JERSEY.

MACHINE FOR OPERATING UPON SHOES.

1,248,791.

Specification of Letters Patent.

Patented Dec. 4, 1917.

Application filed March 13, 1916. Serial No. 83,819.

To all whom it may concern:

Be it known that I, EDWARD H. BASTABLE, a citizen of the United States, residing at South Braintree, in the county of Norfolk and State of Massachusetts, have invented certain new and useful Improvements in Machines for Operating Upon Shoes; and I do hereby declare the following to be a full, clear, and exact description of the invention, such as will enable others skilled in the art to which it appertains to make and use the same.

This invention relates to machines for operating upon shoes, and more particularly to a machine for operating upon the outsole attaching flange of a lasted shoe.

In the manufacture of welt shoes, stitched down shoes and some types of McKay shoes, the outsole is attached to a flange which extends outwardly from the shoe upper. The outwardly extending flange may be the welt or its equivalent, or a portion of the upper, or the edge of a sole attached to the bottom of the shoe. In many types of shoes the out-seam is embedded in the face of the attaching flange, and if the flange is in proper temper the seam can be more readily embedded therein. If the flange is not in proper temper it is necessary to cut a channel or groove 30 in the surface of the flange, in order to embed the seam, and this often results in such a deep cut that the outseam will break through the flange.

The primary object of the present invention is to provide a machine for moistening the outsole attaching flange of a lasted shoe so that it will be in proper condition for the outsole stitching operation.

In accordance with this object, one feature 40 of the invention contemplates the provision in a machine for operating upon shoes having means for supporting a shoe, of a moistening device for moistening the outsole attaching flange of a lasted shoe, comprising 45 a mechanism movable into and out of contact with said flange, and means for supplying liquid to said means.

The preferred form of the invention employs a moistening device which is embodied 50 in a rough rounding and channeling machine. The moisture applying mechanism is attached to the forepart guide, and arranged to be moved into or out of contact with the welt or outsole attaching flange when the 55 forepart guide is moved into and out of con-

tact with the shoe upper. Moisture is supplied to the applying mechanism from a tank which has a valve operated by the movement of the forepart guide so that the moistening liquid will only be admitted to 60 the mechanism when it is in contact with the welt.

The welt or outsole attaching flange should be moistened before the outseam stitching operation. If the welt has been previously 65 moistened for the inseam sewing operation it often becomes dry and hard before it comes to the outseam sewing operation. Also, in many cases, the welt has never been moistened, so that the operator of the out-seam sewing machine usually moistens the 70 welt by hand with a brush before sewing the outsole. This operation is objectionable because it often acts to strain the uppers, and the welt is not thoroughly moistened 75 and has no opportunity to temper. By applying the welt moistening device to the rough rounding and channeling machine, the moisture has ample opportunity to temper the welt before the outseaming operation, and the extra hand moistening operation is not necessary.

Another object of the invention is to provide a moistening device by which the liquid for moistening the outsole attaching flange 85 may be accurately controlled.

In accordance with this object, another feature of the invention contemplates the provision in a machine for operating upon shoes having means for supporting and 90 guiding a shoe, of a device for moistening the outsole attaching flange of a shoe, comprising a flexible liquid applying mechanism for rubbing only the surface of said flange, and means for supplying liquid to said mechanism. The preferred form of liquid applying mechanism consists of a brush which is arranged to rub over the face of the welt. Shields are employed to confine the bristles of the brush to the face of the welt and to 95 hold the brush out of contact with the upper. The moistening liquid is conducted through the center of the brush to the bristles, and the bristles work themselves into the face of the welt and insure that the 100 liquid will be applied to the desired portion of the welt.

Other features of the invention consist in certain features of construction and combinations of parts which are hereinafter de- 110

scribed and pointed out in the appended claims.

The various features of the invention are illustrated in the accompanying drawings, 5 in which Figure 1 is a view in side elevation showing such parts of a rough rounding and channeling machine as are necessary to illustrate the application of the improved moistening device thereto; Fig. 2 is a view in 10 front elevation of the parts shown in Fig. 1; and Fig. 3 is a detail sectional view of the liquid applying brush.

In the drawings the invention is shown as embodied in a rough rounding and channeling machine having the construction fully 15 shown and described in the patent to Perry, No. 1,030,606, granted June 25, 1912. This machine is provided with a work support 10, a rounding knife 12, a channel knife 14, a 20 crease guide 16, and a forepart guide 18. The forepart guide is mounted on an arm 20 which swings about an axis 22 and is connected by means of a link 24 and levers 26 and 28 with a rod 30 which is secured to a 25 foot treadle. The above mentioned parts are fully described and illustrated in the patent above referred to.

The welt is moistened during the rough rounding and channeling operation by a 30 brush which contacts the welt immediately behind the forepart guide 18. The liquid applying brush consists of a hollow stem 32 to which is attached a set of bristles 34. A shield 36 is placed around the bristles, and 35 has a guard 38 on the side adjacent the shoe upper which will contact the upper and hold the brush away from the upper. A guard 40 opposite the guard 38 serves to confine the bristles of the brush to the face of the 40 welt. The stem 32 is mounted in a bracket 42 which is attached to the front end of the arm 20. With this construction the brush will move with the forepart guide, and when 45 the guide is brought into contact with the upper, the brush will be applied to the welt. The stem 32 is adjustable in the bracket 42 relatively to the shoe support 10, and is held 50 in adjusted position by means of a set screw 44. In this way the bristles can be adjusted 55 to press against the face of the welt so that they will work themselves into the uneven face of the welt.

The hollow stem 32 of the brush is connected by a flexible tube 46 with a valve 48 55 which forms the outlet of a supply tank 50 for holding the moistening liquid. This liquid is usually water, but may be any form of solution for properly tempering the welt. The liquid flows down through the hollow 60 stem 32 and comes in contact with the bristles which serve to conduct the liquid to the face of the welt.

The moistening liquid is admitted to the brush only when it is in operation upon the 65 shoe and is automatically shut off when the

brush is not in contact with the welt. To accomplish this result a lever 52 formed on the valve is connected by means of an adjustable link 54 with a swivel 56 which is mounted in the forepart guide arm 20. The 70 forepart guide is used in guiding the shoe when operating about the forepart of the shoe, and is brought into contact with the shoe by the foot treadle. When the guide is brought down into contact with the upper, 75 the valve 48 is set in the position illustrated in Fig. 2, and when the guide is withdrawn from the upper, the valve will be closed. The extent of opening of the valve to control the amount of water admitted to the 80 brush may be varied by an adjustment of the link 54. In this way the different types of wetting may receive the required amount of liquid to properly temper them.

While the invention has been illustrated 85 as applied to a rough rounding and channeling machine, its application is not limited to such use, but the tempering device may be used with any machine which operates upon a lasted shoe after the welt has 90 been beaten out.

Having thus described my invention, what is claimed as new is:—

1. A machine for operating on shoes, having, in combination, rounding and channeling mechanism, and a device for applying liquid to the welt of a shoe to temper said welt during the operation of the rounding and channeling mechanism.

2. A machine for operating on shoes, having, in combination, rounding and channeling mechanism including shoe guiding means comprising a guide movable into and out of contact with the shoe, and a device mounted to move with said guide for applying liquid to the welt of a shoe to temper said welt during the operation of the rounding and channeling mechanism.

3. A machine for operating on shoes, having, in combination, rounding and channeling mechanism including shoe guiding means comprising a guide movable into and out of contact with the shoe, a device mounted to move with said guide for applying liquid to the welt of a shoe to temper said welt during the operation of the rounding and channeling mechanism, a valve controlled supply tank for supplying liquid to said device, and connections between the valve and guide for operating the valve.

4. A machine for operating on shoes, having, in combination, shoe guiding means, a bristle brush for applying liquid to the sole attaching flange of a shoe to temper said flange, and a guard to hold the bristles from the shoe upper.

5. A machine for operating on shoes, having, in combination, mechanism for operating upon the shoe, shoe guiding means including a movable guide means for moving

the guide into and out of contact with the shoe during the operation of said mechanism on the shoe, and a device movable with said guide for applying liquid to the outsole attaching flange of the shoe when the guide is in contact with the shoe.

6. A machine for operating on shoes, having, in combination, shoe guiding means including a guide movable into and out of con-

tact with the shoe, a device movable with 10 said guide for applying liquid to the outsole attaching flange of a shoe to temper said flange, and mechanism connected with said guide and operable by the movement of said guide for admitting liquid to said device 15 only when it is in contact with the flange.

EDWARD H. BASTABLE.
